UNITED STATES PATENT OFFICE.

STEPHEN J. TRACY, OF NEW YORK, N. Y.

CURTAIN-FIXTURE.

No. 893,761.

Specification of Letters Patent.

Patented July 21, 1908.

Application filed January 28, 1908. Serial No. 413,047.

To all whom it may concern:

Be it known that I, STEPHEN J. TRACY, a citizen of the United States, and resident of New York, in the county of New York and 5 State of New York, have invented certain new and useful Improvements in Curtain-Fixtures, of which the following is a specification.

My invention relates to improvements in 10 curtain fixtures.

The main objects are to provide a cheap, simple and readily operable construction for sustaining, opening and closing a pair of curtains or portières.

15 It consists in an improved construction and arrangement of guides, cords and weights, as more fully set forth in the following description and the accompanying single sheet of drawings.

20 Figure 1. is a view showing the complete embodiment of my invention, the curtains being closed. Fig. 2. is a vertical section on the plane of the line *x*, Fig. 1, looking in the direction of the arrow and showing the left 25 hand side weight. Fig. 3. is a vertical section on the plane of the line *y*, Fig. 1, looking in the direction of the arrow and showing the center weight. Fig. 4. is a detail view of one 30 of the end cord guide devices, full size. Fig. 5. is a similar view of the center guide device. Fig. 6. is a detail partial sectional view of the center weight, full size.

The rod 1, is supported in a suitable manner as, for instance, by brackets 2 and 3. 35 The curtains, 4 and 5, are supported by suitable rings or devices such as 6 and 7, which will slide freely on the rod. The end rings are preferably located outside the brackets so as to limit the movement of the curtains.

40 A center guide, 8, and end guides, 9 and 10, are provided for the operating cords or chains which will be hereinafter described. Each guide consists of a split body slightly larger than the curtain rod, a metal strip having 45 ears 11, 11, bent double and terminating in lugs 12, 12, and a wheel or sheave such as 13, for the cord. The ears 11, 11, are riveted or otherwise secured to the body and thus hold it together. This affords a cheap, rigid construction which is easily assembled. A

50 thumb or other screw, 14, is used to clamp the guide on to the rod 1. The center guide has two wheels or sheaves, 15, 15, for the two cords, and a plate, 16, is used to space them

apart and keep the cords from getting out of 55 place.

A cord or chain, 17, is secured to the curtain 4, at intervals, or to the rings 6 in any suitable manner and the ends passed over the wheel of the end guide 9, and one of the center wheels, 15. The other cord, 18, is similarly secured to curtain, 5, or its rings and the ends passed over the wheel of the end guide, 10, and the other center wheel, 15. Weights, 19 and 20, are secured to the outer ends of 60 the cords. The inner ends of the cords are united to an extension cord, 21, which carries the center weight, 22. This center weight is substantially equal to the weight of the two outer ones. To prevent injury to the glass, 70 when the apparatus is used with window curtains, I make the center weight of a bag, 23, filled with sand or shot, 24, so that it is flexible. This allows the weight to bend and yield sufficiently when it is swung and strikes 75 against the glass, so that it is brought to rest gradually and without injury to the glass. I also prefer to cover the weight with a fringe, 25, which serves to increase the yielding effect and is ornamental as well. 80

By this construction it is possible to open and close a pair of curtains by simply raising or lowering the center weight. The arrangement also serves to hold the curtains in any position intermediate "open" and "closed". 85 When the curtains are open the center weight is raised and out of the way. Only one hand is necessary for operating the cords.

What I claim is:

1. A curtain fixture comprising the combination of a rod, two curtains slidably supported therefrom, a center and two end guides, two cords operating through said guides for sliding the curtains, an outer weight for each cord and a center weight common to 95 both cords and counterbalancing the outer weights.

2. A curtain fixture guide comprising a split ring like body for encircling a rod, means for clamping the body to a rod, a 100 metal strip formed with doubled ears secured to the ends of the body and with depending lugs, and a wheel carried by said lugs.

STEPHEN J. TRACY.
